(57) **CLAIM**

The ornamental design for an eyeliner applicator, as shown.

DESCRIPTION

FIG. 1 is a perspective view of an eyeliner applicator;
 FIG. 2 is a right side elevational view thereof;
 FIG. 3 is a left side elevational view thereof;
 FIG. 4 is a bottom plan view thereof;
 FIG. 5 is a top plan view thereof;
 FIG. 6 is a front elevational view thereof; and,
 FIG. 7 is a rear elevational view thereof.
 Broken lines are used to illustrate unclaimed portions of the
 eyeliner applicator; broken lines for no part of the claimed
 design.
